(57) CLAIM

The ornamental design for a shoe with ball and chain, as shown and described.

DESCRIPTION

FIG. 1 is a top, front left perspective view of a shoe with ball and chain showing our new design;

FIG. 2 is a front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The figures include broken, solid and dash-dot-dash lines. The areas within the solid lines and inside the dash-dot-dash lines form the claimed design. The broken lines shown in the figures are included for the purpose of illustrating portions of the shoe with ball and chain and form no part of the claimed design.
